UNITED STATES PATENT OFFICE

AUGUST TECKENBURG, OF HAMBURG, GERMANY

CLOCK WITH AUTOMATICALLY-TRAVELING ADVERTISING SURFACE AND ANNULAR GAP FOR THE CLOCK HANDS

Application filed June 30, 1927, Serial No. 202,668, and in Germany October 29, 1925.

This invention relates to a clock with advertising strip in the dial and moving periodically and automatically, the movement of said band being controlled by an electromagnet, the hands of the clock, which are offset accordingly, circulating cylindrically around the advertising device.

Clocks of similar construction have become known but in these clocks toothed wheels are generally used as means for making the hands circulate around the advertising device and which, to be coupled to a normal clock-work, required a special transmission-gear or abnormal modifications of the clock-work. By the arrangement of hands which, are offset twice, it becomes difficult to find a suitable mounting for the advertising-device and to preserve the facility of inserting and removing the same, it being further necessary to make the driving mechanism for the traveling advertisement band as simple as possible owing to the limited space. The commonly used forms of construction comprise no means for selecting any desired time-period for the traveling of the pictures and for securely preventing the jumping over of one or several pictures.

According to the invention the annular gap between the dial and the advertising area, and serving for the free movement of the offset hands, is bridged by means of U-shaped connecting bows which carry, together with the arbor, the casing for the advertisements. In order to ensure an easy inserting and removing of the advertisement-casing, the two hands of the clock are bent only twice at right angles. The periodic starting of the movement of the advertisement-band is effected by a flat ring, fixed on the minute-hand behind the advertisement-casing and having a number of contact-pins corresponding to the duration of the traveling period, said flat ring controlling the movement of a locking lever which, for the driving wheel of the advertisement band is electromagnetically operated. Jumping of pictures is prevented by an auxiliary locking hook, arranged, besides the main locking hook, on this locking lever and which, when the locking lever does not return at the correct time this return-

movement being retarded by too long circuit-closing, bears in the locking position on the nose of the locking wheel of the driving wheel so that the same can execute always only one rotation.

A clock with advertising mechanism constructed according to the invention is shown, by way of example, in the accompanying drawings, in which:—

Fig. 1 shows in front elevation the clock 60 with ring-shaped dial and advertising surface.

Fig. 2 is a vertical central section on line 2—2 of Fig. 1.

Fig. 3 shows in rear elevation the advertisement-casing, this casing and the clock-casing being shown in section on line 3—3 of Fig. 2.

Fig. 4 shows a top plan view of the clock, one half in section.

Fig. 5 shows the arrangement of the endless advertisement-band, of the driving roller and of the tension roller in the advertisement-casing.

Fig. 6 shows a connecting-bow for the mounting of the advertisement-casing on the 75 clock-case, the bow being shown in two different views.

Fig. 7 shows in two different views a modified construction of the connecting-bow.

Fig. 8 is a connection-diagram for the driving mechanism for the advertisement-band and for the illuminating of the same.

Fig. 9 shows in front elevation and in side elevation the minute-hand with a contact carrying ring.

In the clock-case 1 having a lid 2 on the top and a glass-door 3, the clockwork 4 is arranged which is covered at the rear by a protecting casing 5; in the case 1 the advertisement-casing 6 is further located which contains the whole advertising mechanism and the driving mechanism 7 for the same. The clockcase 1 of any desired convenient shape has in the front wall 8 and in the rear wall 9 a circular aperture 10, the diameter of the aperture in the front wall being of the same size as the aperture in the ring-shaped dial 11.

This dial 11 is fixed on the front wall 8. A closing ring 12, designed to serve as mounting for the glass-door 3 mounted on a

55

60

65

85

90

95

100

- hinge 13, is also fixed on the front wall 8. The clock-work is so arranged that the hand carrying arbor 14 is situated accurately at the centre of the circular aperture 10 or of the ring-shaped dial 11.
- 5 The advertisement-casing 6 consists essentially of two side-walls, designed for journaling the rollers. This casing 6 is open at the top end and stayed by transverse bars 15.
- 10 The casing 6 is mounted on the arbor 14 by means of a connecting bar 16 and consequently supported at the rear end. The front wall 17 of casing 6 is circular and has a square aperture 18. On the wall 17 four or a greater number of narrow but resisting connecting-bows 19 bent in U-shape are arranged, by means of which the casing 6 is fixed on the clock-case. The advertisement-casing is of such diameter that, between the clock-case 20 and the circular front wall of the casing 6, an annular gap 20 is formed which is sufficiently wide to let pass the minute-hand 21 and the hour-hand 22. These two hands are bent first at right angles in forward direction and then 25 again at right angles in outward direction so that, in their rotating movement, they circumscribe a large cylindrical space. The outwardly bent points of the hands pass underneath the U-shaped connecting-bows 19.
- 30 The connecting-bow shown in Fig. 6 may be made separately as one piece, in which case the ring-shaped mounting 12 for the door of the clock-case must have corresponding incisions, or the connecting-bows are made, as 35 shown in Fig. 7, in which case the bow 19 is made in one piece with the ring-shaped mounting 12. The offset portion 23 is in any case so great that the hands 21 and 22 can freely move the one over the other.
- 40 The mechanism in the advertisement-casing consists of a driving work 7 which may either be a spring-work or a small-sized electromotor and from which a driving wheel 24 is rotated. On the shaft of the driving wheel 45 a locking disk 25, having a locking nose 26, is keyed. The rotating movement of the driving wheel 24 is transmitted by an endless belt 27 upon the driving roller 28 which has an annular groove 29, in order that the advertisement-band can pass over the endless belt 27. On the driving wheel 24 and on the driving roller 28 teeth are arranged to prevent slipping of the driving belt and of the advertisement-band. At the side of the driving cylinder 28 a tension roller 31 is arranged which is mounted in vertical slot-bearings of the side walls of the casing and pressed downward by the action of springs 32. Four other rollers 33 serve for guiding the advertisement-band 34. The ends 35 of this band 34 are united by sewing, tying or in any other suitable manner so that an endless band is formed. On the advertisement-band sections 36 on which advertisements are painted and 65 spacing sections 37 alternate.

When the door 3 of the clock-case and the lid 2 are opened the advertisement-band 34 can be easily placed around the corresponding rollers in the manner shown in Fig. 2, whereupon the two ends of the band are connected the one with the other. The advertisement-band is securely held by the tension roller 31. The circumference of the driving wheel 24 is selected so that at each rotation a new section 36 of the advertisement-band appears behind the square aperture 8 to become visible from the outer side. An electric lamp 38 in the advertisement-casing serves to light the advertisements, the cable 39 of said lamp passing over the bows 19 or through the arbor.

70 The mechanism for periodically operating the advertisement-band consists of a flat ring 41, having metal-pins 40 and fixed on the minute-hand of the clock, said ring serving at the same time for balancing said minute-hand as it is loaded at one side; further of contact-springs 42 and 43 which, when coming into touch with one of the pins 40, close the circuit for an electromagnet 44 which 75 then attracts a locking lever 45 so that it releases the locking wheel 25 for rotation. The pins 40 of the flat ring 41 are accurately mounted on a circle, the centre of which coincides with the axis of the clock. According 80 to whether the advertisements have to be changed every 10 minutes or every 5 minutes or every 2 minutes, 6 or 12 or 30 pins 40 are arranged on the flat ring 41. The number of pins multiplied by the number of the minutes 85 of the period must always be 60.

90 The contact-springs 42 and 43 are arranged in such a manner that the pins 40, when passing along the same, touch them both at the same time so that the circuit of a conductor 95 46, which is connected to the light line 39 and passes across the electromagnet 44, is closed for a short time by the pin 40 which is of electricity conducting material, so that current is supplied to the electromagnet.

100 The locking lever 45, which is attracted by the electro-magnet 44, is a two-armed lever, fulcrumed at 50, and has a locking hook 47 and an auxiliary locking hook 48. The end 105 of the locking lever 45 which carries the locking hook 47 is lifted, when said lever is being attracted by the electromagnet, so that the hook releases the nose 26 of the locking wheel 25. The driving work 7 can then rotate the driving disk 24.

110 As soon as the contact-springs 42 and 43 have slipped from the pin 40 of the flat ring 41, the attracting force of the electromagnet ceases and the locking lever 45 is returned 115 into its initial locking position by the action of a spiral-spring 49. After one complete rotation of the locking wheel 25 its nose 26 will butt again on the locking hook 47 and stop the driving wheel 24 and consequently 120 the rotation of disk 25.

When the sliding contact of springs 22 and 23 on a contact-pin 40 should last longer than one rotation of the wheel 25, the nose 26 will butt against the auxiliary locking hook and stop the driving work. As soon as no current flows through the electromagnet and spring 49 pulls upward the lever 45, the locking nose will pass along the auxiliary hook 48 and butt then against the locking hook 47. 5 When another contact-pin 40 comes into touch with the contact springs 42 and 43, the circuit of the electromagnet is closed again, the locking hook 47 is pulled upward and the locking wheel 25 is liberated for another 10 rotation. At every rotation of the locking wheel a new advertising-section 36 appears behind the aperture 18. Separate switches 51 are provided for switching off the electric lamp and the mechanism. 15

In order to prevent the long hands 21 and 22 exerting by their overweight a disturbing influence upon the movement of the clock, they are balanced by small counter-weights 52. For the same reason the contact-springs 25 42 and 43 are made as feeble as possible and the time during which they are in touch with the contact-pins 40 is made as short as possible. The short duration of the contact is further necessary in order that the contact of 30 the electromagnet be interrupted before a full rotation of the locking wheel 25 is completed.

It is evident that slight constructional modifications and improvements may be 35 made. The sector-shaped portions 53 of the front wall of the advertisement-casing might either be ornamented or used for advertising-purposes. The feet 54 of the connecting-bows 19 might be inserted in the wall 17 and 40 coloured with paint or made invisible in any other suitable manner.

I claim:—

1. The combination with a clock including a case with a ring-shaped front portion, and 45 time hands pivotally mounted back of said ring shaped front portion; of an advertising casing mounted in front of the pivotal mounting of the time hands, the front portion of said advertising casing being substantially 50 in the plane of said ring-shaped portion, there being an annular slot between said front portions, one of said portions being provided with dial markings, said time hands being shaped to circumscribe the space occupied 55 by said advertising casing and to project through said annular slot and traverse the dial markings, and bows straddling said slot and the path of said hands and connecting said front portions to support said advertising casing. 60

2. A clock as specified in claim 1, comprising in combination with the connecting-bows, a ring-shaped mounting on the front wall of the clockcase to which said connecting bows 65 are fixed directly so that for removing the ad-

vertising casing it is merely necessary to loosen said mounting.

3. A clock as specified in claim 1, comprising in combination with the advertising casing, an endless advertisement band in said casing, means for guiding and tensioning said advertisement-band, a driving work for said guiding and tensioning means, a flat ring 70 fixed on the minute-hand of the clock behind the advertisement casing, as many contact pins on said flat ring as there are advertising periods per hour, a driving wheel of said driving work, a locking wheel keyed on the shaft of said driving wheel, a locking lever co-operating with said locking wheel, an electromagnet for operating said locking lever, 80 a circuit of said electro-magnet, contact-springs interrupting said circuit and designed to co-operate with said contact pins on said flat ring for periodically closing the circuit 85 so that said locking lever is disengaged from said locking wheel and said driving work operates and moves said advertisement-band, an auxiliary locking nose on said locking lever designed to stop said locking wheel when, 90 owing to excessively long circuit closing in the electromagnet, the locking lever is not released in proper time to stop the locking wheel which thus can execute always only one rotation. 95

In testimony whereof I affix my signature.
AUGUST TECKENBURG.
